UNITED STATES PATENT OFFICE

SAMUEL S. BRADLEY, OF NEW YORK, N. Y., ASSIGNOR TO MANUFACTURERS AIRCRAFT ASSOCIATION, INC., A CORPORATION OF NEW YORK

DESIGN FOR A MEDALLION OR SIMILAR ARTICLE

Application filed November 24, 1931. Serial No. 41,842. Term of patent 14 years.

To all whom it may concern:

Be it known that I, SAMUEL S. BRADLEY, a citizen of the United States, residing at New York, in the county of New York and State of New York, have invented a new, original, and ornamental Design for a Medallion or Similar Article, of which the following is a specification, reference being had to the accompanying drawing, forming part thereof.

Figure 1 is a front elevation of a medallion embodying the present design; and

Figure 2 is a plan view thereof.

This design is adapted to be used upon the instrument panel of an aircraft to orna-

ment the same and comprises a central body in a form representing a nautical compass within a conventional steering wheel, as shown in the figures, the said central body being so arranged with respect to a pair of wings extending from the opposite sides thereof as to give the appearance of being supported thereby.

I claim:

The ornamental design for a medallion or similar article, substantially as shown and described.

In testimony whereof, I hereunto affix my signature.

SAMUEL S. BRADLEY.
